UNITED STATES PATENT OFFICE.

EVAN A. BROWN, OF SANTA MONICA, CALIFORNIA, ASSIGNOR OF ONE-HALF TO
W. E. WILMOT, OF TACOMA, WASHINGTON.

TOOTHBRUSH.

Application filed November 26, 1924. Serial No. 752,420.

My invention relates to tooth brushes, and the purposes of my invention are the provision of a tooth brush adapted to be supported on and manipulated by the finger; a tooth brush comprising a stall formed of fabric or other suitable material which may or may not be impregnated with a tooth cleaning compound and which is adapted to be discarded after being once used; and a tooth brush having on the surface of the stall projections arranged and shaped to facilitate their insertion into the interstices of the teeth and to the inner sides thereof, the projections to be also formed of fabric or other suitable soft material so as to prevent injury to the gums.

I will describe only one form of tooth brush embodying my invention and will then point out the novel features in claim.

20 In the accompanying drawings,

Figure 1 is a view showing in perspective one form of tooth brush embodying my invention;

Figure 2 is a longitudinal sectional view 25 of the brush shown in Figure 1 in applied position to the finger;

Figure 3 is a vertical sectional view taken on the line 3—3 of Figure 2.

Referring specifically to the drawings, in 30 which similar reference characters refer to similar parts in each of the views, my invention, in its present embodiment, comprises a stall 15 open at one end to allow the insertion of the finger and closed at the other end to limit the movement of the finger inwardly of the stall. This stall is preferably formed of cotton or other suitable fabric, which is subjected to suitable pressure to form the finger embracing stall and the tooth engaging 35 projections.

Likewise, the cotton or fabric may be saturated with a cleaning medium or dentifrice prior to the pressing operation to impart body thereto, so that the fabric mass 40 will be more susceptible to formation under the action of the press.

In this manner a tooth cleansing device is formed of compressed fabric to provide a relatively stiff finger engaging stall having 45 destructible tooth engaging projections thereon. The material of which the stall is formed may or may not be impregnated with

tooth cleaning compound, and when impregnated with such a compound eliminates the necessity of applying a tooth paste or powder to the brush.

The stall 15 resultant of the die and pressure operation is formed on its outer surface and at that portion thereof which is disposed to the inner side of the finger when applied thereto with projections 16 in the form of ribs which are preferably wedge-shaped in cross section. These ribs are arranged so that their narrow or working edges are disposed in spaced relation to each other, and such working edges are preferably blunt, as illustrated. The ribs as shown in Figure 1 extend circumferentially of the stall and are tapered or graduated in cross sectional area toward their free ends so that by imparting a rotary motion to the finger to which the tooth brush is applied, the tapered ends of the ribs will be moved into the interstices between the teeth and upon continued movement the thick portions of the ribs so as to bring the tooth cleaning compound into intimate relation with the side edges of the teeth, and to thus effect a thorough cleaning of the teeth, as will be understood.

These ribs 16 extend over a portion of the closed end of the wall and, as will be seen from Figure 2, the ribs are graduated in size toward the closed end of the stall, so that the smaller ribs are disposed on the closed end. To facilitate the cleaning of the inner sides of the incisors, the smaller ribs on and adjacent the closed end of the stall are divided transversely into sections by forming therein transverse grooves 17. It is by means of these ribbed sections that the removal of tartar from the base of the inner sides of the incisors can be effectively accomplished.

In the use of the tooth brush, liquid will tend to run down the surface of the stall onto the finger and to prevent the contamination of the finger the open end of the stall is provided with an annular bead 18, which causes the liquid to remain upon the stall, as will be understood.

Although I have herein shown and described only one form of tooth brush embodying my invention, it is to be under-

stood that such changes and modifications may be made as do not depart from the spirit of the invention and the spirit and scope of the appended claim.

5 I claim as my invention:

A tooth brush comprising a stall formed of fabric material having integral circum-

ferentially extending ribs, wedge shaped in cross section, and diminishing in width toward their ends, and grooves intersecting the ribs at and adjacent the closed end of the stall. ¹⁰
